UNITED STATES PATENT OFFICE.

AUGUST FRITZ, OF CHICAGO, ILLINOIS.

VELOCIPED.

SPECIFICATION forming part of Letters Patent No. 324,826, dated August 25, 1885.

Application filed January 20, 1885. (No model.)

To all whom it may concern:

Be it known that I, AUGUST FRITZ, a citizen of the United States, residing at Chicago, in the county of Cook and State of Illinois, 5 have invented a new and useful Improvement in Hobby-Horse Tricycles, of which the following is a specification, reference being had to the accompanying drawings.

My invention relates to an improvement 10 in hobby-horse tricycles; and it consists in the combination of a hobby-horse which has the neck and a portion to which the fore legs are secured pivoted to the body, a driving-wheel which is secured to the pivoted portion 15 of the body, pedals and cranks for actuating the wheel, and small wheels that are attached to the rear legs of the hobby-horse; and it further consists in the construction and combination of devices that will be more fully 20 set forth hereinafter.

In the accompanying drawings, Figure 1 is a perspective of my invention. Fig. 2 is a vertical longitudinal central sectional view. Fig. 3 is a detailed rear elevation of the driving-wheel and pedal mechanism and the pivotal rod, with the sleeve through which the rod passes in section.

Referring to the letters, *a* represents a hobby-horse, which is preferably made as nearly 30 as possible in the true form of a horse. The neck portion *b*, to which the head is attached, is made separate from the main body of the horse, as at *x*, and the portion *c*, to which the fore legs are attached, is also made separate 35 from the main portion, as at *y*. A pivotal rod, *d*, passes vertically up through the portions *b c* and the front end of the main portion. This rod *d* passes loosely through a metallic sleeve, *e*, which is secured in the 40 main portion, and is connected rigidly to the pivoted portions *b c* by means of bolts *f*, which pass transversely through said pivoted portions and through the pivotal rod. The sleeve *e* is provided with a shoulder, *e'*, near 45 its upper end, and a coiled spring, *g*, is placed on the rod *d*, and bears between said shoulder and the lower pivoted portion, *c*. On opposite sides of the lower end of the rod *d* are secured standards *h*, which are curved at 50 first forwardly, as at *h'*, and then rearwardly,

as at *h''*. In between the lower ends of these standards is journaled the driving-wheel *i*, which is provided with the double-cranked shaft *k*, to which it is keyed. Pedal-levers *l* are pivoted to the standards, as at *l'*, and links *m* connect these levers with the cranks, as shown. The rear legs are connected to the rear axle, *n*, by means of the flat springs *o*, and on the extremities of this axle are journaled the rear wheels, *p*, which are much 60 smaller than the driving-wheel. The saddle *r* is provided with downwardly-projecting lugs *s* at its front end, which adapt it to be pivoted to the back, as at *t*, and the rear portion of the saddle is supported upon a 65 spring, *u*. From the rear end of this spring, which is secured to the body of the horse, as at *u'*, extends a strap, *u''*, which forms the crupper, as shown. By this arrangement the spring is made to look like a portion of the 70 crupper.

Ornamental trappings *v* are so disposed upon the horse as to conceal the dividing-lines *x y*, and a bridle is attached to the head of the hobby-horse, which enables a child seated 75 upon the saddle to direct the course of the tricycle by pulling upon the reins and moving the head in either direction, as will be very readily understood.

The springs which are provided, as de- 80 scribed, prevent concussions while riding over rough or uneven roads, and thus insure ease and comfort to the rider and avoid the danger of causing congestion of the brain, to which children are exposed who use the ordinary tricycles and hobby-horses now in common use.

The pedals are arranged so as to have a direct up-and-down motion, which is both 85 healthful and pleasant to the child rider.

Having thus described my invention, I 90 claim—

1. The combination of the body *a*, pivoted portions *b c*, pivotal rod *d*, having standards *h* depending therefrom, a driving-wheel that 95 is journaled between the standards, cranks *k*, pedal-levers *l*, and links *m*, for actuating the wheel and rear wheels, substantially as described.

2. The combination of the body *a*, pivoted 100

portions *b* *c*, pivotal rod *d*, having standards *h* depending therefrom, spring *g*, and sleeve *e*, a driving-wheel which is journaled between the standards, cranks *k*, pedal-levers *l*, and links *m*, for actuating the wheel, springs *o*, rear axle, *n*, and wheels *p*, pivoted saddle *r*, spring *u*, and a bridle attached to the head of the hobby-horse, substantially as described.

In testimony that I claim the foregoing as my own I have hereto affixed my signature in presence of two witnesses.

AUGUST FRITZ.
